poration of Illinois

Application October 6, 1937, Serial No. 167,499

4 Claims. (CL 158—1)

This invention relates to an apparatus for preventing pulsating in heating devices. It is particularly applicable to domestic oil burning furnaces, and it will be described in connection with such a furnace, although it is to be understood that it may also be used with other heating devices.

When oil burners are used with furnaces having combustion chambers that are substantially pressure tight except for the draft exit, there is a limit to the magnitude of combustion that may occur in the furnace without encountering the phenomenon known as "panting," or pulsating, of the combustion flame. This "panting" is not only undesirable because of the noise and the vibrations that it causes, but also because it causes inefficient combustion and requires a larger furnace for a given capacity than might otherwise be necessary. The present invention is directed to overcoming this difficulty under all conditions under which it tends to occur.

The general object of the invention is to provide an apparatus for preventing pulsating, or "panting," in furnaces.

Other objects and advantages of the invention will appear from the following specification and drawings.

An embodiment of the invention is shown in the accompanying drawings in which:

Figure 1 is a side elevation of a furnace embodying an apparatus for practicing the invention;

Fig. 2 is a partial horizontal section of said furnace on the line 2—2 of Fig. 1;

Fig. 3 is an enlarged side elevation of the oil burner shown in Fig. 1, a portion of the air tube being cut away;

Fig. 4 is a detail end elevation of the closure for the end of the air tube;

Fig. 5 is a detailed sectional elevation of the front end of the air tube;

Fig. 6 is a detailed sectional elevation of a burner showing a modified form of apparatus; and

Fig. 7 is an end view of the air tube of Fig. 6 showing the air deflector in the end of said tube.

The invention is shown applied to an oil-burning, domestic, hot air furnace of well-known construction, suitable for use with modern air conditioning systems where the air is cleaned, heated and forced through ducts to the various rooms of a building. The oil-burning, domestic furnace illustrated has been shown by way of example only and it is to be understood that the invention may be used with other types of substantially

pressure tight furnaces or heating devices using any suitable fuel.

As shown in Figs. 1 and 2, the furnace has a main housing 10, sometimes called a heat exchanger. This housing is L-shaped as viewed from the side, and the two arms of the L are rectangular in cross section, one of them being shown in section in Fig. 2.

10 Mounted in the vertical arm of the L is a fire box 11 which is made of fire resisting material such as fire clay. The box is closed on its bottom and sides, but open at the top. It is preferably pear-shaped in cross section as shown in Fig. 2.

Above the fire box is a space 12 that receives 15 the combustion gases which then pass rearwardly through the passages, or flues 13, to a pipe 14 that leads to the stack or chimney. The fire box and the surrounding housing form an enclosed combustion chamber in which the oil is burned.

The air to be heated is drawn downwardly 20 through the duct 15, through the cleaning screens 16, and around the pipe 14, by a motor-driven blower 17. It is then forced upwardly through 25 the spaces 18 (Fig. 2) between the flues 13 from where it passes upward through the passage 19 to the various ducts leading about the building. The air is thus cleaned, pre-heated, heated, and then forced throughout the building.

An oil burner 20 of any of the many well-known types on the market may be used. Such a burner has an electric motor 21 which forces oil through the feed pipe 22 (Fig. 5) into the fire box in a fine spray, and which also drives a fan 30 that forces air into the fire box through an air tube 23, which ordinarily has an air deflector in its end that causes the air to swirl as it enters the fire box. Such a deflector 24 is shown in Figs. 6 and 7. This deflector leaves the end of the tube quite open and in free communication with the fire box. Suitable electrical ignition points 25 (Fig. 3) are provided to ignite the mixture, and the burner is provided with automatic controls (not shown) to start and stop it in a manner well known in the art.

A finished ornamental casing 26 surrounds the heating chamber and burner to give the completed furnace a finished appearance.

The invention will be more easily understood by first describing the phenomenon of "panting" and then explaining how it is prevented by the method and apparatus disclosed herein.

Assume that an oil-burning furnace is started by closing the oil burner switch by means of a thermostat or otherwise. The motor starts, it

drives the oil pump and the air blower, and a quantity of atomized oil and air is forced into the combustion chamber where an electric spark ignites the mixture. When ignition takes place there is a sudden increase in the volume of gases within the combustion chamber, and the only exit for these gases is through the furnace and chimney. This increased volume of gases and air have before them the column of air, or air and gases, extending from the combustion chamber to the top of the chimney. It would be necessary for this column to move instantly toward the top of the chimney in order to prevent the pressure within the combustion chamber from rising. This column, having weight and being subject to the laws of inertia and momentum, resists any sudden force tending to put it into motion, with the result that pressure within the combustion chamber increases.

The air supplied to the combustion chamber is supplied by a blower which is adjusted to deliver the proper quantity of air for efficient combustion against the normal pressure within the combustion chamber. When the above-mentioned abnormal pressure occurs, the blower fails to supply enough air to complete the combustion and, under these circumstances, the combustion is incomplete. This results in a reduced volume of combustion gases as well as allowing some unburned fuel to accumulate. As a result of this inefficient combustion, the pressure within the combustion chamber decreases. In the meantime, the column of gases leading from the chamber to the top of the chimney has been given some motion through the high pressure condition that has just existed. This column resists any force tending to reduce its velocity. The movement of this column tends to reduce the pressure still more. The air blower is now confronted by an abnormally low resistance to the delivery of the air, with the result that the quantity of air delivered increases above normal. This increase in air, together with the unburned fuel which has accumulated during the low pressure period, combine and the result is that the combustion is greater than normal, which, in turn produces another high pressure condition. These high and low pressure periods follow each other in rapid succession and tend to resolve themselves into a rhythmic cycle known as "panting."

The above-explained condition takes place at the starting of the furnace, and is sometimes designated the "starting surge." It may continue for only a short period or it may continue indefinitely, depending upon conditions.

"Panting" may also occur while the furnace is running, either as a continuation of the "starting surge" or as an independent phenomenon caused by variations in the combustion which start up the rhythmic cycle above mentioned.

When the burner is shut off by opening the switch, the motor slows down. At the instant the burner is shut off, the air blower is delivering the proper quantity of air to the combustion chamber but, as soon as the motor starts to slow down, the delivery diminishes very rapidly. At the same time, the column of air and gases from the combustion chamber to the chimney is moving outward at a certain velocity. As the speed of the motor decreases the air delivered to the blower diminishes rapidly while the air column from the chamber to the chimney top tends to continue to move. This produces a low pressure condition within the combustion chamber which is fol-

lowed by a high pressure period due to the tendency of the air to rush into the low pressure combustion chamber. This phase of the phenomenon of "panting" is very difficult to investigate, owing to the fact that instruments sufficiently delicate and responsive are not available to obtain accurate proof of exactly what conditions exist. It is sufficient to say that the "stopping surge" or "finishing kick" is very similar to the "starting surge" and consists of a series of rapid pulsations that make considerable noise and vibrate the furnace.

Thus, the phenomenon of "panting" may occur when the furnace is started; it may occur during the period the furnace is running; it may take place when the furnace is stopped; and it may occur under any two or more of these conditions. The problem is to prevent it under all conditions.

It has been proposed to remedy the condition by having an opening in the combustion chamber that will allow air to enter in case of a low pressure condition and allow gases to escape during a high pressure condition. This is undesirable owing to the fact that when the air enters the combustion chamber it is cold, it does not enter at the right place, it absorbs heat, and the thermal efficiency of the furnace is reduced. When a high pressure period occurs, the gases escape into the room where the furnace is, which is highly undesirable. While these gases might be vented to the outside of the furnace room, the resulting passage slows down the venting action and is not sensitive enough to give the desired results. This proposed arrangement is not satisfactory.

It has also been proposed to reduce the size of the combustion flame, but this reduces the efficiency of combustion, causes the deposit of soot, makes it impossible for the heating plant to deliver its greatest capacity, and is not a desirable solution.

I have found an inexpensive and efficient method of handling this problem which prevents "panting" under all conditions. This method involves controlling the air supply in such a way that the "panting" or pulsations, cannot get started. The method will be clearer by first describing it in connection with an apparatus for putting it into effect.

Referring to Figs. 1 and 3, the blower 30 for forcing air into the air supply tube 23 is of larger capacity than those normally employed for an oil burner of a given capacity. The larger blower is used in order that a higher static pressure may be obtained, and continued under all working conditions, as will be presently explained.

This will be more clearly understood if the characteristics of a blower are briefly explained. A blower delivers its maximum volume of air in cubic feet per minute at "zero" or no static pressure. As the static pressure increases, as, for example, by the resistance of a passage into which the air is delivered, the volume of the delivery gradually decreases. If a curve is plotted between the delivery in cubic feet per minute represented by horizontal coordinates and the static pressure by vertical coordinates, the curve starts on the base line for static pressure and out horizontally at a point corresponding to the maximum cubic feet per minute delivered by the blower. As the static pressure increases, the curve goes upward with a fairly steep backward slope for a considerable distance, but a point is soon reached where the curve slopes off sharply at almost right angles.

In other words, the static pressure can be increased with only a small decrease in the cubic feet per minute delivered up to a certain point, but, when the static pressure goes above a certain amount, the cubic feet per minute delivered drops off very rapidly. The blower 30 in the present invention is of such capacity that it operates to deliver the proper volume of air at the proper static pressure while the blower is operating on the steep slope of the curve so that any increase in static pressure will not result in any marked decrease in the volume of supply.

Instead of using the usual air deflector in the end of the tube 23, a closure 31 is provided having a plurality of holes 32 in it (Figs. 3, 4 and 5). These holes are formed in the closure 31 so as to give the air a swirling motion as it enters the fire box. The blower 30 builds up a relatively high static pressure behind the closure, the openings 32 being of such size and number as to cause air to be delivered to the fire box in the proper quantity for efficient combustion. This static pressure must be considerably greater than the pressure created by a "starting surge," or by any pulsating surge that may occur within the furnace. In other words, the air must be supplied in sufficient quantity and in the proper manner for efficient combustion; it must be supplied with considerable velocity pressure, and it must be backed by an air supply having a relatively high static pressure. The action under conditions that tend to cause "panting" is then as follows:

Assume that the furnace is started and that a condition of high pressure has been caused by the ignition of the atomized oil. This pressure, however, is not equal to the pressure behind the incoming air. While the pressure within the combustion chamber tends to retard the incoming air, the effect is relatively small owing to the velocity at which the air is entering and the static pressure behind it. The result is that the supply of air to the combustion chamber remains substantially constant. Under these circumstances the increased pressure does not affect the efficiency of combustion and a condition of low pressure is not created. Instead, the flame continues to burn steadily and the pressure created by the initial ignition tends to dissipate itself on the column of air and gases between the chamber and the top of the chimney. The constant supply of air and the pressure behind it prevents the rhythmic action from starting. To put it another way, while the starting pressure tends to create a condition of pulsating, the incoming air chokes the pulsations.

While it is preferable, for reasons that will be explained later, to have the closure 31 for the air pipe 23 at the end of said pipe, it is also possible to have a closure, or baffle, located farther back in the pipe, as indicated at 40 in Fig. 6. In this form, the static pressure is created behind the baffle 40 and the air then goes out through a small opening in said baffle into the front end of the pipe where it is distributed by the usual type of deflector 24.

The exact form of apparatus used to get a static pressure behind the air supply while at the same time controlling said supply so that only the proper quantity of air is delivered may take different forms and the above are merely 70 illustrations.

The apparatus of Figs. 1-4 has the advantage that the end of the air delivery pipe 23 is closed. When this pipe is open a column of air extends from the blower to the delivery end of said pipe. 75

Since air is elastic and may be compressed or rarefied, the air column in the delivery pipe tends to magnify any unstable conditions that may exist in the combustion chamber. For example, if pressure in said chamber is increased, the tendency is for the air in the delivery pipe to be compressed. If the pressure in the chamber is decreased, the air in the delivery pipe tends to be rarefied. This condition is improved with a closure in the end of the pipe having small openings for air delivery. While the combustion chamber is still in communication with the delivery pipe, the communication is through very small openings through which air is coming at high velocity and behind which there is a very considerable static pressure. The air column in the delivery pipe does not magnify any unfavorable conditions in the chamber but, on the contrary, tends to resist changes in pressure in said chamber because the stabilizing effect of the high static pressure is effective at the entrance to said chamber.

While several forms of apparatus have been shown, it is to be understood that the method of accomplishing the results does not depend upon the exact form of apparatus that may be used to put the method into effect. This method involves supplying fuel to an enclosed combustion chamber; supplying air to said chamber in proper quantities for efficient combustion of said fuel; and of maintaining a static pressure behind said air supply higher than any pressure that may be created by a surge and thereby maintaining said air supply substantially constant in the face of changing conditions in said chamber.

I claim:

1. An anti-pulsating furnace having an enclosed combustion chamber which is substantially pressure tight except for the flue exit, means for introducing fuel under pressure into said chamber, means for introducing combustion air into said chamber, said air-introducing means including a device for reducing the air supply near where it is introduced into said chamber, and means for supplying air to said air-introducing means behind said reducing device in such quantity and at such pressure that the static pressure of the air behind said reducing device is maintained considerably in excess of any pressure that may occur in the combustion chamber.

2. An anti-pulsating furnace having an enclosed combustion chamber that is substantially pressure tight except for the flue exit, means for introducing fuel under pressure into said chamber, an air-introducing tube connecting with said chamber having a closure in its inner end provided with one or more small openings communicating with said chamber to introduce combustion air into said chamber and means for supplying air to said tube in such quantity and at such pressure as to maintain the air behind said closure at a high static air pressure considerably in excess of any pressure that may occur in said combustion chamber.

3. An anti-pulsating furnace having an enclosed combustion chamber which is substantially pressure tight except for the flue exit, a gun-type oil burner including oil and air delivery means for introducing oil and air into the combustion chamber, said air-delivery means including a device for reducing the air supply near where it is delivered into the chamber, and means for supplying air to the air-delivery means behind the reducing device in such quantity and at such

pressure that the static pressure of the air behind the reducing device is maintained considerably in excess of any pressure that may occur in the combustion chamber.

4. An anti-pulsating furnace having an enclosed combustion chamber that is substantially pressure tight except for the flue exit, a gun-type oil burner including oil and air delivery means for introducing oil and air into the combustion chamber, said air delivery means comprising an

5 10

air-introducing tube connecting with the chamber having a closure in its inner end provided with a plurality of small openings through which combustion air is introduced into the chamber, and means for supplying air to the tube in such quantity and at such pressure as to maintain the air behind the closure at a high static air pressure considerably in excess of any pressure that may occur in the combustion chamber.

LOUIS E. ARNOLD.
